DESIGN FOR WRAPPING PAPER

Arthur Lewin, New York, N. Y.

Application January 16, 1936, Serial No. 60,623

Term of patent 3½ years

To all whom it may concern:

Be it known that I, Arthur Lewin, a citizen of the United States, residing in New York, county and State of New York, have invented a new, original, and ornamental Design for Wrapping Paper, of which the following is a specification, reference being had to the accompanying drawing, forming part thereof.

The figure of the drawing is a plan view of a piece of wrapping paper showing the repeat unit of the design.

The dominating feature of the design is the assembly of spaced smooth-surfaced diamond-

shaped configurations (A), a plurality of spaced keystone-like figures (B), each with a lateral wedge-like arm (C), a plurality of pebble-faced square diamond-shaped configurations (D), and a plurality of overlapping angular configurations having lined surfaces (E), the direction of the lines of one figure extending angularly of the direction of the lines on a contiguous figure as shown.

I claim:

The ornamental design for wrapping paper, as shown and described.

ARTHUR LEWIN.
